UNITED STATES PATENT OFFICE.

CHARLES W. GIFT, OF FAIRMOUNT, INDIANA, ASSIGNOR TO LUTHER R. GIFT, OF SAME PLACE.

WEATHER-STRIP.

SPECIFICATION forming part of Letters Patent No. 368,917, dated August 23, 1887.

Application filed May 5, 1887. Serial No. 237,207. (No model.)

To all whom it may concern:

Be it known that I, CHARLES W. GIFT, a citizen of the United States, residing at Fairmount, in the county of Grant and State of Indiana, have invented certain new and useful Improvements in Weather-Strips, of which the following is a specification, reference being had therein to the accompanying drawings.

This invention relates to weather-strips. My object is to combine with a door an improved weather-strip, as will be fully understood from the following description, taken in connection with the annexed drawings, in which—

Figure 1 is a perspective view of a portion of a door-casing illustrating my improvement applied thereto. Fig. 2 is a front view illustrating the flap shut. Fig. 3 is a vertical cross-section through the casing and sill, illustrating the door when shut and the flap closed against the sill.

Referring to the annexed drawings by letter, A designates the door casing or frame, and A' the door thereof. Near the lower end of the door A, I secure a bracket, D, which is recessed to receive the upper end of the flap E. This flap, which is practically the weather-strip, has beveled ends, as indicated in Fig. 3. This flap is connected to the bracket D by spring-hinges H, the leaves of which are secured to the upper side of the flap E afford abutments for stop-plates S, which are secured to the bracket on the shutter. These stop-plates should be adjustable by slotting them, as shown in Fig. 2, for the purpose of compensating for wear.

At the hinged side of the door upon the end of the flap E is secured a spring-plate, F, having an upturned portion, a^x, to which may be applied an anti-friction roller. This plate, with its upturned portion a^x, is adapted to bear against a V-shaped cam, G, provided with ears and secured rigidly to the upright part of the casing A in such relation to the flap or weather-strip that in the act of closing the door the said strip will be snugly held to the sill-piece C, the spring-plate serving to receive and relieve the strip of the shock attendant upon closing the door.

At the opposite side of the casing is an inclined flange, B', provided with ears b', and inclined with respect to the lower beveled

edge of the flap E, so that this flap will be directed closely to the sill in closing the door. 55

It will thus be seen that I provide a door with a weather-strip having a spring-hinge for raising it to a given point, adjustable, as stated, and that I have provided a simple device for depressing this strip in the act of closing a door; also, that I have provided an inclined guide which will positively direct the lower edge of the strip to its place upon the door-sill.

Having thus fully described my invention, 65 what I claim as new, and desire to secure by Letters Patent, is—

1. The combination, with a door, of a weather-strip connected thereto by a spring-actuated hinge, a spring-plate, F, provided 70 with an upturned end bearing or buffer, a V-shaped cam secured to the casing of the door, and an inclined plate, B', located at the upright of the threshold of the door, substantially as described. 75

2. In a weather-strip for doors, the combination of the door-frame and door hinged thereto, the recessed bracket or strip D, secured to the door, the hinged strip or flap E, the spring-actuated hinges H, connecting the 80 said strip E to the bracket D, the vertically-adjustable stops secured to the bracket D and adapted to contact with one of the leaves of the spring-hinge H, the spring plate or buffer F, provided with an upturned elastic end, and 85 the angular cam G, secured to the door-frame, all arranged substantially as described.

3. The combination, with the casing and a hinged door or shutter, of a weather-strip attachment consisting of the recessed bracket D, 90 rigidly secured to the door, the adjustable stop-plates secured to said bracket, the flap E, attached to the said bracket by spring-actuated hinges, the spring-plate F, secured to the end of flap, the cam G, secured to one of the 95 door-jams in the relation described to the spring-plate F, and the inclined flange B', secured to the other door-jamb, all constructed and adapted to operate substantially as described. 100

In testimony whereof I affix my signature in presence of two witnesses.

CHARLES W. GIFT.
